ATTACHMENT FOR CARTONS

James C. Haws, Houston, Tex.

Application June 30, 1932, Serial No. 620,123

7 Claims. (Cl. 221—23)

This invention relates to an attachment for cartons.

An object of the invention is to provide an attachment of the character described specially designed for application to cartons, or boxes, such as are commonly used to contain breakfast foods and similar foods and whereby provision is made for the delivery of the contents of the container as desired and which will keep the container securely closed at other times.

Another object of the invention is to provide an attachment of the character described comprising a clamp plate formed of metal or similar material which is adapted to be clamped to a wall of the container and which is shaped to define a section of the wall to be removed to provide an outlet opening and a shutter or closure normally closing said opening but which may be readily opened when it is desired to discharge the contents of the container.

Another object of the invention is to provide an attachment of the character described equipped with a supplemental foraminated cover whereby the carton may be used as a shaker for serving salt and the like.

The attachment has been designed particularly for application to boxes or cartons containing food, but it is capable of general application to containers of this general nature.

With the above and other objects in view, the invention has particular relation to certain novel features of construction, operation and arrangement of parts, an example of which is given in this specification and illustrated in the accompanying drawings, wherein:

Figure 1 shows a top plan view of the container showing the attachment applied thereto and in open position.

Figure 2 shows a fragmentary sectional view thereof taken on the line 2—2 of Figure 1.

Figure 3 shows a sectional view of the container showing the attachment in position to be applied thereto,

Figure 4 shows an underside view of the attachment in open position.

Figure 5 shows a top plan view of the container equipped with a supplemental perforated cover shown in closed position.

Figure 6 shows a top plan view thereof showing the main cover plate, in open position, and the supplemental cover in position for use.

Figure 7 shows a top plan view showing the main cover plate and the supplemental cover in open position.

Figure 8 shows a fragmentary vertical sectional view of the form shown in Figure 5.

Figure 9 shows a fragmentary side elevation of the container showing still another form of the attachment.

Figure 10 shows a fragmentary vertical sectional view thereof, and

Figure 11 shows an inside view of the form of attachment shown in Figure 9.

Referring now more particularly to the drawings wherein like numerals of reference designate similar parts in each of the figures, the numeral 1 designates a clamp plate, which is preferably formed of metal, and which has its central portion cut away forming the opening 2. The outer end of this clamp plate is downwardly turned forming the stop 3 adapted to abut the opposing wall of the carton or box 4, when the attachment is applied thereto. Underneath the clamp plate 1 there are the clamp prongs 5, 5 which are preferably formed integrally with the outer end of said clamp plate and whose inner ends are pointed as at 6, 6. The inner margins of these clamp prongs 5 are in substantial alignment with the corresponding sides of the cutaway portion 2.

Hinged to the inner margin of the clamp plate 1 there is a cover plate 7 which may be of the same general contour as the clamp plate. In application the attachment is applied to the box 4, in a manner indicated in Figure 3, and the points of the prongs 5 are forced through the material of one wall of the box, and forced on inwardly until the clamp plate 1 lies on the adjacent wall of the box as indicated in Figure 2, in which position the said last mentioned wall will be gripped between the clamp plate 1 and the prongs 5. The material of the box defined by the opening 2 may then be bent away to provide an outlet opening for the contents of the box. The free end of the cover plate 7 has a spring clip 8 which is flexible and whose free end is outwardly curved. When the cover 7 is in closed position this clip will fit down closely over the overturned portion 3 of the clamp plate 1 and said overturned portion 3 has a stud or projection 9 which will be received by a socket 10 in the clip 8 whereby the cover will be held tightly closed.

In the form shown in Figures 5 to 8 inclusive the clamp plate 1 is similar to that shown in Figure 1 and is secured to the carton or box 4 by the prongs 5 in the manner hereinabove described. In this form however there is a supplemental cover plate 11 preferably rectangular in form, which is located underneath the cover plate 12. This supplemental cover and the cover plate are

mounted to pivot about the pivot 13 whereby said supplemental cover 11 and the cover plate are secured to the clamp plate 1. In this form the cover plate 12 may be swung around into one position as shown in Figure 6 so as to expose the perforations of the cover 11 when it is desired to use the container as a shaker. The cover plate 12 has the upstanding grip 14 at its free end whereby it may be swung about its pivot. When 10 the cover plate 12 is swung around in the other direction it will engage the stop 15 carried by the cover 11 and may be stopped in said position to completely close the opening but if moved further in said direction as indicated in Figure 7, it will 15 carry the cover 11 with it so as to completely open the opening 2.

In the form shown in Figures 9, 10 and 11 there is a clamp plate 16, preferably circular in form and having the central opening 17 defining the portion of the container to be cut away. This 20 clamp plate 16 has the inside prongs 18 whose free ends are sharp and correspondingly directed and provided to be inserted through the material of the container and the clamp plate is turned until said prongs are forced through the material of the container wall, said prongs serving to secure the plate 16 in place. In this form there is a circular cover plate 19, pivoted to the clamp plate 16 at one side whereby the cover 25 plate 19 may be swung either into open or into closed position. This cover plate 19 has the upstanding grip 20 by means of which it may be manipulated. The cover plate 19 also has the depending marginal stops 21 which engage the clamp plate 16 when the cover plate is swung to closed position so that it will be stopped in said last mentioned position. The cover plates 7, 12 and 19 may be readily opened when it is desired to remove a portion of the contents of the box or container and at other times may be maintained securely closed to exclude moisture and foreign matter and to keep the contents of the box or container fresh.

The drawings and description disclose what are now considered to be preferred forms of the invention by way of illustration only, while the broad principle of the invention will be defined by the appended claims.

What I claim is:

50 1. A device of the character described comprising a clamp plate having a cutaway portion, clamp prongs carried thereby one on each side of said cutaway portion, and a closure hinged to

and adapted to fit closely against said clamp plate and adapted to cover said cut away portion when in closed position.

2. A device of the character described comprising a clamp plate having a discharge opening therethrough, clamp prongs on opposite sides of the opening and secured to said plate and lying adjacent thereto and approximately parallel therewith and having free ends, and a cover plate hinged to the clamp plate and adapted to close 85 said opening when in closed position.

3. A device of the character described comprising a clamp plate having a cutaway portion, clamp prongs carried thereby, and a closure hinged to said clamp plate and adapted to cover 90 said cut away portion when in closed position, and a spring on said closure and engageable with the outer end of said plate for maintaining said cover plate in closed position.

4. A device of the character described comprising a clamp plate having an opening, a plurality of prongs attached at one end to said plate and lying approximately parallel therewith and having their other ends free and pointed and a cover plate hinged to the clamp plate and movable 95 into one position to open said opening and into another position to close said opening, and releasable means for maintaining said cover plate closed.

5. In combination a container, a clamp plate 105 fitted against an outer side thereof, and having a cutaway portion defining an opening, means for releasably securing said clamp plate in position, a cover plate hinged to be moved out of and into close fitting relation with said plate so 110 as to open and close said opening.

6. A device of the character described comprising a clamp plate having an opening therethrough, clamp prongs carried thereby and arranged about the opening and adapted to clamp 115 a carton wall between them and said plate and a closure movably attached to said plate and adapted to be moved into open and closed position.

7. A device of the character described comprising a clamp plate having a discharge opening therethrough, means for securing said plate to a container, a perforated cover and a cover plate movably mounted with respect to said clamp plate and relatively movable into and out of coinciding 125 position to open and close said opening.
